UNITED STATES PATENT OFFICE.

FLOYD W. NEWMAN, OF BRADFORD, PENNSYLVANIA.

DOOR.

No. 796,142.

Specification of Letters Patent.

Patented Aug. 1, 1905.

Application filed May 3, 1904. Serial No. 206,232.

To all whom it may concern:

Be it known that I, FLOYD W. NEWMAN, a citizen of the United States, residing at Bradford, in the county of McKean and State of Pennsylvania, have invented a new and useful Door, of which the following is a specification.

My invention relates to doors, window-shutters, or similar closures, and has for its objects to produce a comparatively simple inexpensive device of this character composed of a series of leaves or sections adapted when the closure is in open position to fold or nest into compact form, thus insuring the closure assuming an unobstructing position when open and one in which the closure may be locked in its closed or other desired position and will when released move automatically to open position.

To these ends the invention comprises the novel features of construction and combination of parts more fully hereinafter described.

In the accompanying drawings, Figure 1 is an elevation of a door embodying my invention, illustrating the same in closed position. Fig. 2 is a similar view showing the door open. Fig. 3 is a section on the line 3-3 of Fig. 1 looking downward in the direction of the arrow. Fig. 4 is a sectional elevation, the section being taken on the line 4-4 of Fig. 3. Fig. 5 is a detail sectional elevation, on an enlarged scale, taken on the line 5-5 of Fig. 3.

Referring to the drawings, 1 designates the vertical side bar or stile of a door or window casing or frame of the usual or any appropriate construction and material and having pivoted thereto by screw-bolts or analogous attaching devices 2 a series of leaves or sections 3, preferably composed from sheet metal and constituting the door or closure, the outer ends of said leaves being individually pivoted by means of bolts or analogous members 4 to a vertical connecting member or strip 5. The leaves or sections 3, which are of uniform width and have their inner ends cut away or rabbeted, as herein shown at 6, have their adjacent or meeting edges slightly overlapped, whereby as the closure is moved to open position said leaves will ride upon and fold neatly and compactly one over another, as seen in Fig. 2, while the heads of the screws or devices 2 are countersunk in order that they may offer no hindrance to this action or folding of the leaves, the heads of the bolts 4 being similarly countersunk to avoid contact with the frame-bar 1. It is to be noted that

owing to the inner ends of the leaves being rabbeted, as shown, they will not project beyond the adjacent edge of the stile during the opening movement of the door and that the connecting member 5 is parallel to and travels in parallelism with the stile during the movement of the door to open or closed position and that during such movement the sections 3 rotate upon the bolts 2 as axes.

Formed in or otherwise provided on the connecting member 5 and in alinement with the outer end of one of the sections 3 is a hollow enlargement or case 7, transversely through which and beyond the adjacent end of the section 3 there extends a knob-spindle 8, carrying a pair of knobs 9, of the usual construction and disposed on the opposite sides of the door, there being fixed upon the spindle 8, within the case, a disk or other suitable operating member 11, having pivotally connected therewith a pair of oppositely-extending latching members or bolts 12 13. The bolt 12 normally projects through a suitable opening in the casing for engagement with a keeper provided on the adjacent door-jamb (not shown) in order to relieve the door of transverse strains or movement, while the bolt 13, which works in a suitable guide 14 provided on the adjacent section 3 of the door, normally projects into engagement with a keeper 15, fixed upon said door-section, this keeper being preferably in the form of a circular ratchet-wheel surrounding the pivoting-bolt 4 of the section. The bolts 12 13 are maintained in and moved automatically to their normal automatic engagement by means of a spring 16, surrounding the spindle 8, within the casing, it being apparent that when the spindle is turned in the proper direction both bolts will be simultaneously retracted against the action of the spring for releasing the door. It may be said that the bolt 13 through its engagement with the keeper 15 serves, as is apparent, to lock the door in its closed position and that during the movement of the door from closed to open position the same may be locked at any intermediate point or position by moving the bolt 13 into engagement with the keeper, which while in such engagement will obviously prevent movement of the door in either direction.

For moving the door automatically to open position when released, as above explained, I provide a series of actuating-springs 17, housed, respectively, within tubular sleeves or casings 18, seated in appropriate sockets

provided in the stile 1, there being a number of the springs corresponding to and coiled, respectively, around the pivoting-bolts 2. These springs and their attendant mechanisms are identical in construction and operation, and I will therefore describe but one in detail, referring more particularly to Fig. 5, in which it will be seen that each spring has one of its ends fixed in an appropriate manner, as at 19, to the wall of the sleeve 18, which in turn is fixed against rotation within stile 1, the other end of the spring being fixed to a primary cam member or head 20, fixed upon the bolt 2 and provided with cam-faces 21, adapted for coöperation with corresponding cam-faces 22, provided on the adjacent end of the sleeve 18, for a purpose which will presently appear. The head 20 constitutes a closure for one end of the sleeve, the other end of which is closed by means of a secondary head 23, likewise fixed upon the bolt 2 and normally bearing against the adjacent inner face of the section 3 to maintain the latter in firm engagement with the head of the bolt.

In practice the springs 17, which are appropriately wound for the purpose, will serve upon the release of the door to move the same automatically to open position by folding the sections 3 one upon another, it being obvious that during this action the bolts 2 will be rotated by their respective springs 17, and that thus each spring will lift the weight of its particular section 3 and a proportionate part of the weight of the connecting member 5. When the door is in closed position, with the sections 3 unfolded, the cam-faces 21 22 will coöperate for drawing the bolts 2 inward with respect to the casings, and consequently maintaining the sections 3 firmly and snugly against the adjacent face of the stile 1. When, however, the opening movement of the door begins, the cam-faces will coact for moving the bolts longitudinally outward with respect to their casings, thus loosening and giving sufficient play to the sections 3 for them to ride readily one upon another in folding. It is apparent that the door when opened will occupy comparatively little space and offer practically no obstruction and that in its movements or when at rest it will be free from looseness, rattling, and other similar objectionable features attendant upon doors now in common use.

From the foregoing it is apparent that I produce a comparatively simple inexpensive device admirably adapted for the attainment of the ends in view, it being understood that minor changes in the details of construction herein set forth may be resorted to without departing from the spirit of the invention.

Having thus described the invention, what is claimed is—

1. In a closure of the class described, the combination with a fixed stile, of a series of

leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, and hand-operated means carried by the closure for rendering the same rigid.

2. In a closure of the class described, the combination with a fixed stile, of a series of leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, and means carried by the closure to render the same rigid consisting of a hand-controlled interlocking connection between the frame-bar and one of the leaves.

3. In a closure of the class described, the combination with a fixed stile, of a series of leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, and hand-controlled locking means operating between the frame-bar and one of the leaves and consisting of a lock carried by one of said members and a keeper carried by the other member.

4. In a closure of the class described, the combination with a fixed stile, of a series of leaves individually pivoted to the stile with their adjacent edges overlapped and capable of being turned into longitudinal alinement to open the closure, a frame-bar extending across the free ends of the series of leaves with the latter individually pivoted thereto, a handled lock carried by the frame-bar, and a keeper upon one of the leaves for engagement with the lock to render the structure rigid in any position of the leaves.

5. In a closure of the class described, the combination with a fixed stile, of a plurality of leaves individually pivoted to the stile with their adjacent edges overlapped and capable of being turned into longitudinal alinement to open the closure, a frame-bar extending across the free ends of the series of leaves with the latter individually pivoted thereto, a toothed wheel upon the pivotal connection between one of the leaves and the frame-bar, a guide upon said leaf, and a handle-lock carried by the frame-bar and including a bolt working in the guide and engaging the toothed wheel to render the structure rigid in any position thereof.

6. In a device of the class described, the combination with a support, of a plurality

of leaves pivotally connected therewith and having their adjacent edges overlapped, said leaves being movable to folded or unfolded position, means tending constantly to automatically move the leaves to one of said positions, and means for locking them against movement.

7. In a device of the class described, the combination with a support, of a plurality of leaves pivotally connected therewith and adapted to fold one upon another, means tending constantly to automatically move the leaves to folded position, and means for locking them against movement.

8. In a device of the class described, the combination with a support, of a plurality of leaves adapted to fold one upon another, pivoting-axles connecting the leaves respectively with the support, a plurality of springs applied respectively to the axles and acting thereon to move the leaves to folded position, and means for locking the leaves against movement.

9. In a closure of the class described, the combination with a fixed stile, of a series of leaves individually pivoted to the stile with their adjacent edges overlapped and capable of being turned into longitudinal alinement in parallelism with the stile, a frame-bar extending across the free ends of the series of leaves with the latter individually pivoted thereto, a spring mounted upon the pivotal support of one of the leaves and tending constantly to automatically move the leaves to folded position, locking means carried by the frame-bar and engaging one of the leaves to render the structure rigid in any position thereof.

10. In a closure of the class described, the combination with a fixed stile, of a series of leaves individually pivoted to the stile and capable of being folded into longitudinal alinement in substantial parallelism with the stile, a frame-bar extending across the free ends of the series of leaves with the latter individually pivoted thereto, a stationary casing inclosing the rotatable pivot of one of the leaves, a helical spring within the casing with one end fixed thereto, a cam-head fixed to the opposite end of the spring, the adjacent end of the casing having a cam-face coöoperating with the cam-head, and means carried by the frame-bar for

engagement with one of the leaves to render the structure rigid in any position thereof.

11. In a closure of the class described, the combination with a fixed stile, of a series of leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, and a lock carried by the frame-bar and including a bolt capable of being projected at the outer edge of the bar.

12. In a closure of the class described, the combination with a fixed stile, of a series of leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, a keeper carried by one of the leaves, and a lock carried by the frame-bar and provided with a bolt to engage the keeper and also having another bolt capable of being projected at the free edge of the bar.

13. In a closure of the class described, the combination with a fixed stile, of a series of leaves individually pivoted upon the stile with their adjacent longitudinal edges overlapped and capable of being turned into longitudinal alinement to open the closure, a frame-bar extending across the free ends of the series of leaves with the latter individually pivoted thereto to effect simultaneous folding of the leaves, a keeper upon one of the leaves, and a lock carried by the frame-bar and including a tumbler, a bolt actuated by the tumbler and coöperating with the keeper, and another bolt actuated by the tumbler and capable of being projected at the free edge of the frame-bar.

In testimony that I claim the foregoing as my own I have hereto affixed my signature in the presence of two witnesses.

FLOYD W. NEWMAN.
